DISPENSING DEVICE WITH REPLACEABLE CARTRIDGE

Vincent E. Dewees, Jenkintown, and George A. Ferris, Philadelphia, Pa., assignors to Kenmar Manufacturing Company, Philadelphia, Pa., a copartnership
Filed Feb. 26, 1962, Ser. No. 175,470
2 Claims. (Cl. 222—326)

This invention relates to dispensing devices with replaceable cartridges containing the material to be dispensed.

It has heretofore been proposed to provide dispensing devices with replaceable cartridges. Most of these have had a frame extending forwardly from the operating head in which the piston rod and rod actuating structure is mounted with the dispensing end of the cartridge held at the front end of the frame, the rear end of the cartridge being held by the frame and also by the advancing piston and piston rod. The removal and insertion of the cartridge involved difficulties in manipulation with possibility of misalignment of the rear end of the cartridge and difficulties in insertion of the piston into the rear end of the cartridge.

It is the principal object of the present invention to provide a piston and cartridge type of dispensing device in which the cartridge is held entirely at the rear end and at the same time is readily insertable and removable.

It is a further object of the present invention to provide a piston and cartridge type of dispensing device in which the cartridge has an end rim with simple but effective structure on the head for receiving and retaining the cartridge end rim.

It is a further object of the present invention to provide a piston and cartridge type of dispensing device in which the cartridge has an end rim with simple but effective structure for receiving and releasably holding the cartridge end rim.

It is a further object of the present invention to provide a piston and cartridge type dispensing device in which a rotatable element is provided for facilitating the insertion of the cartridge rim for retention and for permitting removal of the cartridge when desired.

Other objects and advantageous features of the invention will be apparent from the description and claims.

The nature and characteristic features of the invention will be more readily understood from the following description, taken in connection with the accompanying drawings forming part thereof, in which:

FIGURE 1 is a perspective view of a dispensing device in accordance with the present invention;

FIG. 2 is a vertical longitudinal sectional view taken approximately on the line 2—2 of FIG. 1;

FIG. 3 is a transverse sectional view taken approximately on the line 3—3 of FIG. 2;

FIG. 4 is a fragmentary sectional view showing the gripping of the rear end of the cartridge; and

FIG. 5 is a fragmentary sectional view similar to FIG. 4 but showing the rear end of the cartridge in spaced relation to its seat as upon insertion or removal.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings, the dispensing device preferably includes a head frame 10 which can be of well known type made of sheet metal with a fixed handle 11, and with an end housing 12 secured thereto.

2

The head frame 10 and end housing 12 can have aligned openings 13 and 14 for the reception of a rotatable and axially movable piston rod 15. The piston rod 15 has a piston 16 at the front end, a rear bent end 17 and intermediate its ends ratchet teeth 18.

A movable trigger 19 can be provided pivotally mounted in the frame 10 on a pivot pin 20, with a ratchet 21 urged by a spring 22 into engagement with the ratchet teeth 21 when the piston rod 15 is oriented for this purpose. An abutment 23 for the spring 22 can be provided in the trigger 19. A retaining ratchet 24, urged by a spring 25 and carried on a pivot pin 26 in the frame 10, prevents retrogression of the piston rod 15. A stop pin 27 in the frame 10 serves as an abutment for the spring 25 and as a stop for limiting forward movement of the trigger 19.

The structure just described is known in the art, and the invention hereinafter to be described is particularly suitable for but is not limited to use therewith.

20 In accordance with the invention a cartridge 30 for the material to be dispensed is provided and is of a flexible material, such as polyethylene or the like. The cartridge 30, if prefilled, can have a closure plug 29 therein. The cartridge 30 has a tubular body 31 and at the front 25 or free end thereof can be provided with any desired type of discharge control device 32 which can be a nozzle or the like integral with the body 31. The body 31, at the rear end thereof is provided with a rim 33 projecting outwardly a distance of the order of the thickness of the 30 cartridge body 31.

The end housing 12 has a peripheral ring 34 internally threaded as at 35 for the reception of the complementally threaded portion 36 of a nut 37. The nut 37 has a rear cylindrical bore section 38 of a diameter to receive the 35 body 31 of the cartridge 30 and a rear end face 39 for engagement with the front end of the rim 33. The nut 37, extending forwardly of the bore section 38 has a flared or frustoconical bore section 40 for guiding and compressing the rim 33 upon movement of the rim 33 40 therealong. The nut 37 can have a knurled band 41 therealong to facilitate manual turning. The end housing 12 has a rim seating plate 42 secured thereto in any desired manner, such as by a screw 43. The plate 42 has a forwardly extending central portion with a curved seat 45 44 to urge the rim 33 radially outwardly upon engagement of the rim 33 therewith by tightening of the nut 37.

The mode of operation will now be pointed out.

If desired, for the initial installation of a cartridge 30, the nut 37 can be slipped over the body 31 so that 50 the end face 39 is brought into engagement with the end of the rim 33. The nut 37 can then be inserted into the end housing 12 with the threads 36 engaged with the threads 35. Upon tightening of the nut 37 the rim 33 is brought into engagement with the seat 44, and further 55 tightening of the nut 37 tends to spread the rim 33 slightly to provide a strong grip. As the piston 16 is advanced by movement of the trigger 19 with ratchet 21 engaging the teeth 18, the contents of the cartridge 30 can be delivered as determined by the movement of the trigger 19. 60 The ratchet 24 prevents undesired reverse movement of the piston rod 15.

When the contents of the cartridge 30 have been discharged, or if it is desired to remove the cartridge for any reason, the piston rod 15 is turned upwardly a sufficient extent to release the ratchet teeth 18 from their engagement by either or both of the ratchets 21 and 24 and retracted a short distance.

Upon loosening the nut 37 so that the end face 39 does not hold the rim 33 against the seat 44, the flexibility of the rim 33, upon application of a manual withdrawing force will permit unseating of the rim 33 from its engagement with the end face 39. The rim 33 can then be

drawn through the bore 38 (see FIG. 5) and the bore 40 for complete separation of the cartridge 30.

Upon initial or subsequent installation of a cartridge 30, with the nut 37 partially loosened or backed off, the rim 33 of a cartridge is first introduced into the bore 40 and upon further inward movement through the bore 38 in distorted condition (see FIG. 5). Upon still further inward movement just past the end face 39 the rim 33 expands, with the body 31 along and close to the bore 36. Upon tightening of the nut 37 the rim 33 is gripped and held as previously explained.

The cartridge 30 can readily be inserted or removed with the nut 37 in place but retracted from its gripping position whereby a saving of time and effort is effected. The insertion and removal of a cartridge 30 does not require any special skill nor special tools.

We claim:

1. A dispensing device having a head frame with a fixed handle and having a cylindrical end housing extending therefrom, said end housing having an interiorly threaded peripheral ring, a transversely disposed plate at the inner end of said ring, a nut threaded at its rear end in said ring and having a rear end face and a central opening extending forwardly from said face, a dispensing cartridge having a body with a flexible rim insertable rearwardly through said opening and engageable with said rear end face and said plate, an actuating rod slidably mounted in said head frame, actuating members for said rod carried by said head frame, and a member on said rod movable in said cartridge for discharge of the contents thereof, the central opening of said nut at the for-

ward end thereof having a tapered interior portion for contracting said rim upon engagement of the rim therewith.

2. A dispensing device having a head frame with a fixed handle and having a cylindrical end housing extending therefrom, said end housing having an interiorly threaded peripheral ring, a transversely disposed plate at the inner end of said ring, a nut threaded at its rear end in said ring and having a rear end face and a central opening extending forwardly from said face, a dispensing cartridge having a body with a flexible rim insertable rearwardly through said opening and engageable with said rear end face and said plate, an actuating rod slidably mounted in said head frame, actuating members for said rod carried by said head frame, and a member on said rod movable in said cartridge for discharge of the contents thereof, the central opening at the forward end thereof having a tapered portion for compressing said rim and between the rear end face and the tapered portion having another portion for passage of said rim in compressed condition.
